UNITED STATES PATENT OFFICE.

EDWARD L. BUSHMAN, OF EAST ORANGE, NEW JERSEY; KENNETH L. CURTIS, OF NEW YORK, N. Y.; AND JOSHUA WARD, OF ELIZABETH, NEW JERSEY, ASSIGNEES, BY DIRECT AND MESNE ASSIGNMENTS, TO BATES VALVE BAG COMPANY, OF CHICAGO, ILLINOIS, A CORPORATION OF WEST VIRGINIA.

BAG-FILLING MACHINE.

Application filed May 7, 1925. Serial No. 28,551.

This invention relates to valve bag filling machines and more particularly to machines which are adapted to feed a predetermined weight of material into bags to be filled.

5 An object of the invention is to provide an accurate weighing machine. A feature of the invention is that the bag is partially supported at the top on a resiliently held swiveled filling spout which is carried separately from the weighing scale upon which the bottom of the bag is adapted to rest.

10 The invention consists in the novel features, arrangements and combination of parts embodied by way of example in the apparatus hereinafter described as illustrating the preferred form of the invention, and the invention will be more particularly pointed out in the appended claims.

15 Further objects and advantages of the invention will more fully appear from the following description taken in connection with the accompanying drawings which show, by way of example, the present preferred embodiment of the invention.

20 Referring to the drawings in which the same reference characters indicate the same parts in the various views:

25 Fig. 1 is a side elevation of the machine, with certain parts broken away, showing the machine in filling position.

30 Fig. 2 is a similar view showing the machine in nonfilling position.

35 Fig. 3 is a detail view of the gate and associated parts.

40 Fig. 4 is a section taken on line 4—4 of Fig. 2.

45 Fig. 5 is a section taken on line 5—5 of Fig. 2.

50 Fig. 6 is a section taken on line 6—6 of Fig. 2.

55 Fig. 7 is a modification of filling spout arrangement.

60 Fig. 8 is a section taken on line 8—8 of Fig. 7, and

65 Fig. 9 is a detail of parts of Fig. 8.

70 Before taking up a detailed description of the machine a general description will be given, setting forth some of the most important features in a general way. A feed hopper, for holding the filling material, is supported adjacent the top of the frame structure. A centrifugal impeller or other suitable feed means is provided adjacent the

lower end of this hopper for forcefully feeding the material; and a feed throat is provided adjacent this impeller and has an opening in register with a bag filling spout. The filling spout is pivotally connected to the frame of the machine at a point somewhat to the rear of the feed hopper, and the spout is supported by a resilient means. The feed throat is provided with a gate which is operated by gravity to close the feed throat. This gate is held in open position by a trigger mechanism which is released when the resilient supporting means is overcome. A weighing scale is arranged below the spout and is provided with a table for partially supporting the bag to be filled; the bag also being supported jointly by the feed spout.

75 The resilient means has a fixed elasticity which may be overcome by a weight far less than the weight of material to be fed into the bag; and the scale weight is variable to regulate the predetermined mass or weight to be placed in the bags. The total predetermined weight required in a bag is equal to the weight necessary to overcome the elasticity of the spring plus the weight necessary to balance the scale weight. When this weight is reached the resilient means will yield sufficiently so that the trigger mechanism will operate to release the gate which will then close the feed throat.

80 Referring to the drawings and more particularly to Figs. 1 and 2:

85 A hopper or bin 1 for holding filling material, such for example as cement, is supported by upright members 2—2* and 3—3* which are attached at their lower ends to base members 4—4*. Rear upright members 5—5* are also attached to base members 4—4* and diagonal brace members 6—6* are attached to the upper ends of members 5 and 3 and 7 and 3* respectively. Diagonal 90 brace members 7—7* are attached to the uprights 3—3* adjacent the hopper 1 and to the lower portion of uprights 5—5* respectively. A member 8 is attached to the uprights 3—3* and a member 9 is attached to the uprights 100 5—5* and tie rods 10—10* preferably made of angle iron are attached at their respective ends to the members 8 and 9.

105 The lower end of the hopper 1 is provided with a discharge throat 11 connected rigidly thereto and provided with an opening 11* in

register with a tubular filling spout 12. This spout comprises a tube shaped body and a suitable guide frame or open superstructure 12^a projecting forwardly therefrom. This 5 guide is preferably formed by a U member whose sides are attached to the side walls of the tube and whose closed end extends forwardly and is supported by a member extending upwardly and rearwardly and attached 10 at its rear end to the top of the tube. This guide may be made slightly yieldable, as by making the U member and its cooperating support of spring wire. The feed spout 12 is pivotally attached to the supports 15 13-13^a which are pivotally mounted on bolts 14-14^a passing through the respective tie rods 10-10^a. The rods 13-13^a extend rearwardly from the pivot bolts 14-14^a and are free to be moved about their pivot points 20 14-14^a within certain limits fixed by the stops 15-15^a attached to the tie rods 10-10^a adjacent the rear ends of the rods 13-13^a. A bracket 16 is attached to the rods 13-13^a at a point intermediate the pivots 14-14^a 25 and the stops 15-15^a and carries at its upper end a trigger stop 17.

A tie rod 18 is pivoted at one end to a lug 18^a attached to the member 8 and its other end is pivotally attached to a part rigid 30 with the spout 12. This tie rod, together with the pivoted rods 13-13^a serve to hold the spout 12 snugly against the face of the throat 11 at all times. The maximum vertical movement of the spout 12 with respect 35 to the valve 11 is relatively small, in the present embodiment being approximately $\frac{1}{8}$ ".

The spout 12 and the forward end of the rods 13-13^a are supported from the bracket 40 19, attached to the upper end of the upright members 2-2^a, by means of the U bolt 20, helical coil spring 21 and link 22. An arm 23 is attached to the lower end of the link 22 and extends forwardly, being pivoted at 45 its forward end with a down-turned portion to which is pivotally connected the front end of a weight 24, provided with a serrated lower portion 25. The rear end of the weight 24 is pivotally connected to 50 the lower end of a link 26, the upper end of which is pivotally connected to an arm 27 which is pivoted to the lower end of the link 22 and provided with an upwardly extending lever 28.

55 A trigger 29 is pivoted to the bracket 30 attached to the lower end of the hopper 1 and carries at its lower end a hook 31 and at its upper end is adapted to be engaged by the lever 28. A suitable bracket such as 32 60 is attached to the tie rods 10-10^a adjacent the bracket 17, and extends upwardly therefrom. A bell crank 33 is pivoted to the upper end of the bracket 32 and carries on one crank end a rod 34 to the end of which is 65 attached a weight 35, and its other crank

end carries a lever 36 adapted to be engaged by the trip stop 17. The lever 36 is pivotally connected to a rod 37 slidably engaged by a rod 38 which passes through a suitable bearing 39 attached to the lower end of the 70 hopper 1 and provided at its front end with a handle 40. At the junction point of the handle 40 and rod 38 a shoulder 41 is provided for engagement with the lever 28.

Operatively associated with the throat 11 75 is a gate 42 provided with a gate opening 42^a which is adapted to be vertically moved to close the throat opening 11^a. This gate 42 carries a catch 43 attached adjacent its upper end and adapted to be engaged by the hook 29, and when so held the throat 11 is in operative position to discharge the filling material with the opening 11^a in communication with the spout 12. The upper end of the gate 42 is (see also Fig. 4) slotted 80 as at 43^a and is engaged by one arm 44 of a bell crank 45 which is pivoted to a suitable bracket 46 secured to the uprights 2-2^a and the other arm 44^a of the bell crank 45 is adapted to be engaged by an abutment 47 carried on the rod 38. A weight 48 is attached to the lower end of the gate 42.

A shield or guide plate 49 is suspended 85 from the spout 12 and forms a means for holding the filled bag away from the upright 2 and other parts of the supporting structure.

Scale supports 50 and 50^a are attached to the uprights 2, 3 and 5; and 2^a, 3^a and 5^a, respectively, at points slightly above the 100 members 4-4^a. Fulcrum points 51 and 51^a are attached to intermediate points of the members 50 and 50^a, respectively. Supported on these points are scale beams 52 and 52^a which carry knife edges 53-53^a and 105 54-54^a at their front and rear ends respectively. A platform or other suitable supporting portion 55 is provided with downwardly extending bearing portions 56-56^a adapted to engage the knife edges 53-53^a 110 respectively. A weight 57 is provided with downwardly extending bearing portions 58-58^a adapted to engage the knife edges 54-54^a respectively. A vertical strut 59 is rigidly attached at its upper end to weight 115 57. One end of a tie rod 60 is pivotally connected to the lower end of the strut 59 and the other end of the tie rod 60 is pivotally connected to a member 61 rigidly attached to the supports 50 and 50^a and extending horizontally therebetween. A second tie rod 62 has one end pivotally attached to the member 61 and its other end is pivotally attached to a vertical strut 63 which is rigidly connected to the platform 55. 120 An auxiliary rider-weight 64, slidably mounted on the beams 52-52^a, is provided to allow for finer adjustment of the scale.

It will therefore be seen that, due to the 125 parallel link motion comprising the beams 130

52—52^a, the tie rods 60—62, the struts 59—63 and their associated parts, the scale platform 55 is restricted to a vertical movement and is prevented from tipping side-
wise. All of which will be clearly understood by those skilled in the art.

The feed hopper 1 is provided with a suitable centrifugal impeller 65 adapted to forcefully feed the filling material out 10 through the opening 11^a and through the spout 12 in register therewith when the gate 42 is in open or operative position. This centrifugal impeller is driven by any suitable motive means (not shown).

15 *Modification of filling spout.*

This invention is not limited to machines in which the filling spout is movable, but may embody various modifications in which 20 the filling spout is fixed with respect to the feed hopper; one embodiment of such modification being shown in Figs. 7, 8 and 9. In this modification a filling spout, designated as 66, is rigidly attached to the discharge 25 throat 11 and is provided at its adjacent forward end with an annular flange 67 cooperatively seated in an annular recess formed in the member 68, sufficient clearance being allowed between the flange 67 and the 30 member 68 to permit of the necessary vertical movement of the member 68, as will be more clearly understood following. A collar 69, provided with a forwardly extending semi-elliptical flange bevelled downwardly 35 and inwardly from its outer edge, is attached to the forward face of the member 68; and extending therefrom and supported thereby is a grid frame 70 which may be made in the form of a slightly yieldable structure. 40 The member 68 is attached to and supported by the rearwardly extending member 71 which is connected to the lower end of the link 22 which in this modification is bifurcated at its lower end in order to permit of 45 its free vertical movement with respect to the fixed spout 66. The shield 49 is attached to the lower extremity of the link 22 and the pivoted rods 13—13^a are attached to the respective sides of the bifurcated link 22. A 50 rod 72 is pivoted at its forward end to the link 22 at a point somewhat above the spout 66 and its rear end (not shown) is pivotally attached to a stationary part of the machine. The rod 72 together with the rods 13—13^a 55 and associated parts form a parallel link mechanism which restrains the movement of the member 71 and recessed member 68 to a vertical motion. The trip lever 28 and the serrated portion 25 are mounted in a manner 60 similar to that described heretofore, but with slightly altered dimensions to accommodate this new position, all of which will be well understood by those skilled in the art. The gate 42 is the same as that heretofore de- 65 scribed and the mechanism for releasing the

gate and returning it to its normal position is the same as that heretofore described.

It will therefore be seen that member 71 together with its bag support 70 is adapted to be moved vertically with respect to the 70 filling spout 66; this relative motion in the present embodiment being approximately $\frac{1}{8}$ ".

It will be understood that other parts of the machine not specifically described in 75 connection with this modification are the same as those embodied in the complete machine heretofore described.

It will be understood by those skilled in the art that although only one unit is shown 80 by way of describing this invention yet a plurality of units, such as described, may be mounted side by side as is usually the custom in this type of machine; in such a case the feed hopper will extend the entire 85 length of the machine and will be common to all of the units, and a centrifugal impeller will be provided for each discharge throat.

90 *Opération.*

Referring to Fig. 1, the hopper 1 having been filled with filling material and the impeller 65 placed in operation by suitable motive means, an empty bag is inserted over the end of filling spout guide means 12^a and 95 spout 12 and the handle 40 pulled forward. This carries the abutment 47 forward and moves the arm 44 of the bell crank 45 upwardly, thereby moving the gate 42 into position to open the discharge throat 11, thereby placing the opening 11^a into communication with the spout 12. Simultaneously with this operation, and also brought about by the forward movement of the rod 38, the stop 41 is moved forward and the trigger 29 100 is permitted to gravitate into a vertical position where the hook 31 will engage the catch 43 to hold the gate in open position; also the lever 28 being released by the stop 41 is moved forward by the weight 24, 105 thereby allowing the serrated edge 25 to engage the top of the bag at this time being filled and to hold it on the guide 12^a and adjacent the spout 12. The trip 17 is now in engagement with the lever 36 thereby allowing the rod 38 to remain in its forward position. The commencement of the filling position is shown in Fig. 1.

The filling material is now being fed out 110 through the throat 11 and the spout 12 and is passing into the bag, which is being supported jointly by the tension spring 21 and the platform 55 of the weighing scale. In the present embodiment the spring 21 will withstand a given force before yielding and the 115 scale supporting the bag from the bottom requires a given force in order to overcome the counter-balance weight 57. In other words, the scale is always exerting a fixed upward force against the bottom of the bag. It will 120

therefore be seen that when the weight of the bag and material has reached the total desired predetermined weight, the spring 21 will receive a downward force equal to the difference between the desired predetermined weight and the weight necessary to balance the weight 57, which will be equal to the force necessary to overcome the resiliency of the spring 21. This will cause an elongation in the spring 21 and the spout 12 will move downwardly about the pivot points 14-14^a causing a corresponding upward movement of the rear end of the bars 13-13^a, which carry the trip 17. As this trip 17 is raised, the lever 36 is released and the balance weight 35 moves downwardly, thereby pulling the links 37 and 38 rearwardly, which causes the stop 41 to engage the trip lever 28; and the stop 47 to engage the arm 44^a of the bell crank 45, thereby moving the end 44 downwardly in the slot 43^a. The trip lever 28 is thereby pulled against the trigger 29 which disengages the latch 31 from the catch 43 and allows the gate 42 to be moved downwardly in response to the pull of weight 48, thereby closing the throat 11. The movement of the trip lever 28 also raises the serrated edge 25, to thereby release the bag so that it might be moved. At this time, the bag is still partially supported from the bottom and is also supported from the spout 12 and guide 12^a.

The filled bag is now removed and the load having been removed from the spring 21, it returns to its normal position carrying with it the spout 12 which returns the rods 13-13^a to their normal position and moves the trip 17 back to its normal position. This completes a cycle of operation, and the machine is now in position to repeat the operation as above described.

When it is desired to vary the mass or weight of material placed in the bags it is merely necessary to change the weight 57, and for a finer adjustment also the rider-weight 64.

In the operation of the machine incorporating the modified spout structure, the bag is placed in position on the support 70 with the edge of the bag nearest the machine passing over the forwardly extending collar 69 and thence around the lower part of the spout 66, and when in this position the end of the spout 66 will be extending into the bag. It will therefore be seen that the flange 67 will prevent the filling material from passing out between the member 71 and the spout 66. The operation of the machine is similar to that heretofore described except that in this modification the spout remains stationary and the support 70 moves downwardly when the bag is filled; thereby moving the rods 13-13^a downwardly to operate the mechanism associated therewith in a manner similar to that heretofore de-

scribed. This modification furnishes a simple and durable supporting mechanism which is free from any of the disadvantages which may attend mechanism in which the spout is movable with respect to the feed 70 hopper. In this modification as well as in the embodiment heretofore described the spout is free from the weighing scale mechanism.

Having thus described our invention with particularity with reference to the preferred embodiment of the same, and having referred to some of the possible modifications thereof, it will be obvious to those skilled in the art after understanding our invention, that other changes and modifications may be made therein without departing from the spirit and scope of the invention, and we aim in the appended claims to cover such changes and modifications as are within the scope of the invention.

What we claim is:

1. In a valve bag filling machine the combination of a spring supported substantially horizontal valve bag filling spout adapted to extend into a bag, a discharge throat in register with said filling spout, and a scale provided with a bag supporting portion, said spout and scale jointly providing means for supporting a bag while it is being filled. 95

2. In a valve bag filling machine the combination of a discharge throat, a gate for said throat, a valve bag filling spout in register with said throat, resilient means supporting said spout, a scale provided with a bag supporting portion, said spout and scale jointly providing means for supporting a bag while it is being filled, and control means for said gate operated by the yielding of said resilient means. 100

3. In a valve bag filling machine the combination of a supporting structure, a discharge throat carried thereby, a gate for said throat, a valve bag filling spout in register with said throat and pivoted to said structure, resilient tension means supporting said spout, a scale provided with a bag supporting portion, and means operated by the pivotal movement of said spout to move said gate to thereby close said throat. 110

4. In a valve bag filling machine the combination of a discharge throat, a pivotally supported valve bag filling spout in continuous registration therewith, resilient means supporting said spout, a gate for said throat, locking means to hold said gate in open position, and control means operated by the yielding of said tension means for releasing said locking means to thereby move said gate to close said throat. 120

5. In a valve bag filling machine the combination of a discharge throat having an opening, a valve bag filling spout having an opening in register with said throat opening, resilient means and a weighing scale for 125

jointly supporting a bag to be filled, a gate for said throat, a lock, a trip lever for releasing said lock, and means for operating said trip lever controlled by the yielding of said resilient means, to thereby close said throat opening.

6. In a valve bag filling machine the combination of a discharge throat having an opening, a valve bag filling spout having an opening in register with said throat opening, resilient means and a weighing scale

for jointly supporting a bag to be filled, means for closing said throat opening, and means operated by the yielding of said resilient means for operating said closure means to thereby close said throat opening. 15

In testimony whereof we have signed our names to this specification.
